Primary Examiner — David Muller(74) *Attorney, Agent, or Firm* — Fish & Richardson P.C.**CLAIM**

The ornamental design for an ear swab, substantially as shown and described.

DESCRIPTION

FIG. 1 is a front view of a first embodiment of an ear swab;

FIG. 2 is a top view thereof; and,

FIG. 3 is a bottom view thereof.

The front view is identical the left, right, and rear views.
